ROD BENDING APPARATUS

Filed Nov. 11, 1929

FIG. 2.

Fig. 3.

PETER BEGHETTI, INVENTOR.
BY Miller, Bogart & Reid. ATTORNEYS.

UNITED STATES PATENT OFFICE

PETER BEGHETTI, OF SAN FRANCISCO, CALIFORNIA

ROD BENDING APPARATUS

Application filed November 11, 1929. Serial No. 406,379.

This invention relates to apparatus for bending rods and the object of the invention is to provide a simple manually operated device for bending rods for building construction to U shape as used for beam hangers and the like.

In the drawings Fig. 1 is a perspective view of my apparatus with a pile of rods in place ready for the first bending operation.

10 Fig. 2 is an enlarged cross section of the apparatus as seen from the line 2-2 of Fig. 1.

Fig. 3 is an enlarged section through the side frame member of the apparatus as seen from the line 3-3 of Fig. 1.

15 In further detail the apparatus comprises a frame having longitudinal side pieces 1 firmly secured to cross members 2 and 3, and slideable base plates 4 and 5.

Base 5 carries a vertical plate 6 for aligning 20 the ends of a pile of rods 7 aligned one over the other between uprights 8 carried on base 3, and further aligned between posts 9 and 10 carried by base 4. Posts 9 and 10 are locked together on top to prevent spreading open 25 by means of a flat bar 11 hinged at 12 to one of the posts, engaging a slot 13 in the other post and held by a nut 14 whereby the bars may be clamped in place if required.

End base 5 may be set at various points 30 along the frame by means of bolts 15 fitting into any of the holes 16.

The rods extend forwardly beyond posts 9 and 10 and rest on a rail 17 which curves around on top of frame member 1 to extend 35 parallel therewith for a distance as shown in Fig. 1 and which rail takes the weight of the stack of rods during the bending operation.

To bend the rods I provide a yoke 18 pivoted at 19 to the forward side of post 10 40 and fitted with a vertical roller 20 arranged to contact the side of the stack of rods, while a lever handle 21 projecting forwardly from the yoke provides means whereby an operative may swing the yoke in direction of the 45 arrows to thereby carry the roller in contact with the rods and bend all simultaneously to the dotted position 7'.

After the first bend, stop 22 is released from side rail 1 of frame by pulling out pin 23 50 and moved toward the rear of the frame the

required distance for the U bend desired and its pin dropped through one of the holes 24 provided, and the base 4 slid along until it strikes the stop, and after which the bending operation is repeated to form the return or 55 U bend.

An additional locking pin 25 is provided in base 4 which may be dropped through holes of the frame.

Post 9 is rounded or has its left-hand corner removed as at 9' so that the rods can be bent further than at right angles if desired, and post 10 is well braced as at 26 to resist the strain.

In practice the apparatus is firmly secured 60 to a heavy frame or foundation to bring it to a convenient working height.

Attention is drawn to the fact that while I show the apparatus with the rods arranged in superimposed relation, the apparatus could be turned on its side so that the layer of rods would be horizontal instead of vertical.

I claim:

1. A rod bender comprising a frame, guides thereon adapted to hold a row of rods in side by side relation, means for aligning the ends of the rods, a movable bending device adapted to contact the side of the row of rods for bending the same simultaneously upon moving the device, a pair of rigid members at opposite sides of the row of rods, a base upon which the members are mounted, and means whereby the base may be set at various positions along the frame relative to the means for aligning the ends of the rods. 75

2. A rod bender comprising a frame, guides thereon adapted to hold a row of rods in side by side relation, means for aligning the ends of the rods, a movable bending device adapted to contact the side of the row of rods for bending the same simultaneously upon moving the device, a pair of rigid members at opposite sides of the row of rods, a base upon which the members are mounted, a locking bar tying the free ends of the members together, and means whereby the base may be set at various positions along the frame relative to the means for aligning the ends of the rods. 80

3. A rod bender comprising a frame, guides thereon adapted to hold a row of rods in side by side relation, means for aligning the ends of the rods, a movable bending device adapted to contact the side of the row of rods for bending the same simultaneously upon moving the device, a pair of rigid members at opposite sides of the row of rods, a base upon which the members are mounted, a locking bar pivoted to one of the members and engageable with the other member for tying the free ends of the members together, and means whereby the base may be set at various positions along the frame relative to the means for aligning the ends of the rods.
4. A rod bender comprising a frame, a plurality of pairs of upright members on said frame spaced and arranged to hold between them a row of horizontal rods positioned one above the other forming a vertical layer of rods, one pair of said members comprising posts provided with releasable means for locking them together above the row of rods, a swinging lever pivoted to one of the posts provided with a member adapted to contact the side of the layer of rods for bending the same against one of the posts upon swinging the lever, said releasable means for locking the posts together being independent of the swinging lever.
5. A rod bender comprising a frame, a plurality of pairs of upright members on said frame spaced and arranged to hold between them a row of horizontal rods positioned one above the other forming a vertical layer of rods, one pair of said members comprising posts provided with means for locking them together above the row of rods, a swinging lever pivoted to one of the posts provided with a member adapted to contact the side of the layer of rods for bending the same against one of the posts upon swinging the lever, and a track supporting the outer ends of the rods curved to follow the path of bending.
6. A rod bender comprising a frame, a plurality of pairs of upright members on said frame spaced and arranged to hold between them a row of horizontal rods positioned one above the other forming a vertical layer of rods, one pair of said members comprising posts provided with means for locking them together above the row of rods, a swinging lever pivoted to one of the posts provided with a member adapted to contact the side of the layer of rods for bending the same against one of the posts upon swinging the lever, and means for positioning said posts at various positions along the rods for forming a second bend in the rods.
7. In a structure as specified in claim 4, a base upon which said posts are mounted 65 slidable along the frame and means for lock-

ing the base at various points along the frame.

8. In a structure as specified in claim 4, a base upon which said posts are mounted slidable along the frame and means for locking the base at various points along the frame including a stop adapted for pre-positioning along the frame and against which said base may abut.

9. A rod bender comprising a frame, a plurality of pairs of upright members on said frame spaced and arranged to hold between them a horizontal row of rods positioned one above the other forming a vertical layer of rods, one pair of said members comprising posts provided with releasable means for locking them together above the row of rods, a swinging yoke lever pivoted to one of the posts provided with a roller adapted to contact the side of the layer of rods for bending the same against one of the posts upon swinging the lever, said releasable means for locking the posts together being independent of the swinging lever.
